UNITED STATES PATENT OFFICE

145,770

DESIGN FOR A TOOL CARRIER

Francis Lawrence Ayres, Chicago, Ill., assignor to Stewart-Warner Corporation, Chicago, Ill., a corporation of Virginia

Application October 8, 1945, Serial No. 122,639

Term of patent 14 years

(Cl. D33—19)

To all whom it may concern:

Be it known that I, Francis Lawrence Ayres, a citizen of the United States, residing at Chicago, in the county of Cook and State of Illinois, have invented a new, original, and ornamental Design for a Tool Carrier, of which the following is a specification, reference being had to the accompanying drawing, forming part thereof.

Fig. 1 is a front elevational view of the tool carrier showing my new design;

Fig. 2 is an end elevational view thereof; and Fig. 3 is a plan view thereof.

The side opposite the front shown in Fig. 1 is substantially the same in appearance as the front side.

I claim:

The ornamental design for a tool carrier, substantially as shown and described.

FRANCIS LAWRENCE AYRES.
